CLAIM

The ornamental design for an oil pan as shown and
described.

DESCRIPTION

Cross-reference is made to U.S. Utility patent application
Ser. No. 17/468,227, now issued as U.S. Pat. No. 11,661,
869, titled “Oil Pan Assembly,” filed Sep. 7, 2021, and all of
which is expressly incorporated herein by reference.

FIG. 1 is an upper perspective view of an oil pan, showing
our new design;

FIG. 2 is a lower perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines show portions of an oil pan that form no
part of the claimed design.

1 Claim, 8 Drawing Sheets

Related U.S. Application Data

a continuation of application No. 29/749,677, filed on Sep. 8, 2020, now Pat. No. Des. 979,622.
